UNITED STATES PATENT OFFICE.

WILLIAM E. GRANNON, OF NEW RICHMOND, INDIANA.

SIDE-BOARD ATTACHMENT FOR GRAIN-WAGONS.

SPECIFICATION forming part of Letters Patent No. 761,476, dated May 31, 1904.

Application filed October 28, 1903. Serial No. 178,901. (No model.)

To all whom it may concern:

Be it known that I, WILLIAM E. GRANNON, a citizen of the United States, residing at New Richmond, in the county of Montgomery and State of Indiana, have invented new and useful Improvements in Side-Board Attachments for Grain-Wagons, of which the following is a specification.

My invention relates to new and useful improvements in side-board attachments for grain-wagons; and its object is to provide a simple and inexpensive device of this character which may be readily placed in position upon either side-board of a wagon and which can be adjusted to protect the contents of the wagon from the elements and also as a shield for the driver.

With the above and other objects in view the invention consists in the novel construction and combination of parts hereinafter more fully described and claimed, and illustrated in the accompanying drawings, in which—

Figure 1 is a side elevation of the body of a wagon having my improved attachment upon one of the side-boards thereof. Fig. 2 is an end elevation of said wagon-body and attachment, the wagon-body being broken away to show the side-board-engaging device. Fig. 3 is a detail view of the brace-lock, and Fig. 4 is a detail view of one of the leaves of a hinge of the attachment.

Referring to the figures by numerals of reference, 1 is a wagon-body of any suitable construction, having straps 2 arranged on the sides thereof for the reception of tongues 3, projecting downward from the side-boards 4. Secured to each end of the wagon-body is a strip 5, having a lug 6 projecting laterally therefrom, the outer end of said lug being normally contacted by a spring-band 7, which is secured to the strip 5 in any suitable manner. The lugs 6 are adapted to project into apertures 8, formed within brace-rods 9, which are pivoted to the ends of a board 10, having hinge-leaves 11 secured thereto. Each of these leaves engages a second leaf 12, which is forked, as shown at 13, and engages the side-board 4 and the side thereunder of the wagon-body. By pressing outward upon the rods 9 the same can be quickly released from the lugs 6, and by lifting the board 10 the

forked leaves 12 can be removed from engagement with the wagon-body and placed in any desired position.

As shown in dotted lines in Fig. 2, the board 10 can be lowered in position over the wagon-body to protect the contents thereof from rain, snow, &c., and by raising the board above the wagon-body into the position as shown by dotted lines the driver of the wagon standing within the body 1 can also be protected from the elements. By moving the board 10 into a vertical position it will serve as a shield against the wind, and by swinging it outward into the position illustrated in dotted lines in Fig. 2 it can be employed as a grain-board for directing material into the wagon.

It will be seen that the device is extremely simple and inexpensive in construction and can be readily attached to any form of wagon. It can be easily reversed, and therefore can be arranged at either side of the wagon-body.

In the foregoing description I have shown the preferred form of my invention; but I do not limit myself thereto, as I am aware that modifications may be made therein without departing from the spirit or sacrificing any of the advantages thereof, and I therefore reserve the right to make such changes as fairly fall within the scope of my invention.

Having thus fully described my invention, what I therefore claim as new, and desire to secure by Letters Patent, is—

The combination with a wagon-body, and a cover hinged to one side thereof and adapted to extend over the body and rest upon the sides and ends thereof; of a strip secured to one end of the body, a lug projecting laterally therefrom, a spring retaining-strip secured to the first-mentioned strip and normally contacting with the end of the lug, and an apertured brace-rod pivoted to the cover and adapted to engage the lug and to be held thereon by the spring-strip, whereby the cover may be locked at desired angles to the wagon-body.

In testimony whereof I affix my signature in presence of two witnesses.

WILLIAM E. GRANNON.
